UNITED STATES PATENT OFFICE.

JOHN D. ISAACS, OF OAKLAND, CALIFORNIA.

STREET CABLE RAILWAY.

SPECIFICATION forming part of Letters Patent No. 326,120, dated September 15, 1885.

Application filed October 30, 1884. (No model.)

To all whom it may concern:

Be it known that I, JOHN D. ISAACS, of Oakland, Alameda county, State of California, have invented a certain Improvement in Cable Railways, of which the following is a specification.

This invention relates to underground tubes for cable railways; and more particularly it relates to the setting and construction of the supporting brackets which carry the boxes of the rope-carrying pulleys.

The invention consists in a peculiarity in the form of the brackets and the means employed to secure them firmly in position.

In the accompanying drawings, forming part of this specification, I show two views, that in Figure 1 being a transverse sectional elevation of a tube at just where a carrying-pulley occurs, Fig. 2 being a plan of the pulley and its bracket as it will set with relation to the surrounding concrete.

In both figures the same letters of reference refer to like parts.

Heretofore tubes for cable railways, when made of concrete, have been provided with iron yokes or frames to which the remaining iron-work of the tube has generally been directly or indirectly connected, so that this iron-work has been in most cases entirely relied upon to support the boxes of the carrying-pulleys, the concrete being used simply to form the tube and foundation for paving, &c. In the present construction the concrete itself is relied upon to act as anchorage and support for the pulley-brackets, the yokes heretofore used being dispensed with.

In the drawings, A is the mass of concrete forming the tube, which in most cases will extend on either side to make a foundation for the rails B.

C is the slot for the grip shank.

D is my pulley-bracket, made, as shown in Fig. 2, to surround the pulley E in plan. At d d this bracket will have recesses to hold the boxes F, which carry the journals of the pulley-spindles G.

H H are the bolts holding the bracket firmly anchored to the concrete.

The bracket has supporting flanges on either side which rest in the molded recesses I I.

The anchor-bolts are built in the concrete when the tube is formed, and, while they serve to more securely fasten the bracket in place, they may in some cases be dispensed with, and the bracket, if made sufficiently heavy and well fitted in the recesses I I, will be found quite secure from movement.

This form of support for the boxes of the carrying-pulley spindles is solid and firm, easily removed and replaced without interfering with the operation of the road, and is cheap and simple to construct and put into operation.

What I claim as my invention, and desire to secure by Letters Patent, is as follows:

In combination with a concrete tube for underground cable railways, the frame or bracket D, made in plan to surround the carrying-pulley, and supporting on each side the boxes for the pulley-spindle, and having projections resting in recesses molded in opposite sides of the tube, so that the bracket will be firmly held in place, and a clear drainage way be left on bottom of the tube, substantially as and for the purpose herein described.

JOHN D. ISAACS.
